Primary Examiner—Philip S. Hyder

(21) Appl. No.: **29/103,767**

(57) **CLAIM**

(22) Filed: **Apr. 21, 1999**

The ornamental design for a cartridge cutting, puncturing, and sealing tool, as shown.

(51) LOC (7) Cl. **08-03**

DESCRIPTION

(52) U.S. Cl. **D8/98; D8/14**

FIG. 1 is a top plan view of a cartridge cutting, puncturing, and sealing tool, showing my new design;

(58) Field of Search **D8/14, 98, 105, D8/101; 30/280, 278, 283, 289**

FIG. 2 is a front elevational view thereof;

(56) **References Cited**

FIG. 3 is a bottom plan view thereof;

U.S. PATENT DOCUMENTS

FIG. 4 is a rear elevational view thereof;
